[57] CLAIM

The ornamental design for a combined illuminated sign and control housing for vehicles, as shown and described.

DESCRIPTION

FIG. 1 is a perspective view of a combined illuminated sign and control housing for vehicles showing my new design, with the cord broken away in the center to indicate indeterminate length and with the broken line showing for illustrative purpose only and forming no part of the claimed design;

FIG. 2 is a front elevational view thereof;

FIG. 3 is a left side elevational view side thereof, with the opposite side being a mirror image, except for the control panel and cord; and,

FIG. 4 is a top plan view thereof.

FIG. 1.
